Primary Examiner—Alan P. Douglas*Assistant Examiner*—Ann Hunt*Attorney, Agent, or Firm*—Oblon, Spivak, McClelland,
Maier & Neustadt**[57] CLAIM**The ornamental design for paper feeder for copying
machine, as shown and described.**DESCRIPTION**FIG. 1 is a top, front and right side perspective view of
paper feeder for copying machine showing my new
design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a cross-sectional view thereof taken on line
8-8 in FIG. 2; andFIG. 9 is a top, front and left side perspective view
thereof; the dotted line portion depicting a copying
machine is shown for illustrative purpose only and
forms no part of the claimed invention.FIG. 1
